STRAND TREATING APPARATUS

Peter J. Knaus, Hinsdale, Ill., assignor to Western
Electric Company, Incorporated, New York,
N. Y., a corporation of New York

Application December 30, 1941, Serial No. 424,843

5 Claims. (Cl. 91—32)

This invention relates to strand treating apparatus, and more particularly to apparatus for coating strands.

Insulating sheathings on electrical conductors are made in many ways, some of which include the application of hardenable materials applied in liquid, semi-liquid, or pasty form and subsequently hardened to a bare or previously sheathed strand. Thus materials in the nature of paint, enamel, varnish, or waxes, asphalts, paraffins and the like dissolved in volatile vehicles, artificial resins hardenable by polymerization induced by heat, and other analogous materials, are used for one or another specific purpose. In many such instances a solvent or vehicle is used which is volatilized and is subsequently recovered; a considerable part of the cost of the coating operation may arise out of the volume of such solvent or vehicle to be recovered for subsequent re-use. Hence it is desirable to apply the raw sheathing or sheath treating materials as a smoothly plastic highly viscous paste, in order that the volume of vehicle or solvent circulated in the process, or perhaps wasted, may be kept low.

In coating or impregnating previously covered wire strands with cellulose acetate considerable difficulty has been experienced in providing a die that will both produce an even coating and prevent escape of the coating material from the coating chamber. Variations in the size of the strand require an aperture capable of dilating to permit passage. The pressure of the coating material on the other hand requires that the aperture be fitted tightly enough to permit only sufficient material to pass with the wire to satisfactorily coat the same. Rubber corks such as used for bottle stoppers have been provided with a hole in the center for the wire to pass through but with ordinary stopper-shaped dies no compensation is possible for variations in the pressure of the coating material.

Also in previously used rubber dies considerable difficulty has been had from "popping." "Popping" results from the accumulation of coating material in the die until it tends to clog the die, at which point the clog "pops" out of the die, carried by the forward motion of the strand.

An object of the present invention is to provide simple, reliable and easily interchangeable means for applying to strands of a considerable range of diameters, material whose physical state is that of a smoothly plastic but highly viscous and thick paste to form a uniform coating on the strands.

With the above and other objects in view, the

invention may be embodied by providing an apparatus to apply coating material to a strand comprising a chambered body to contain the material and formed with entrance and exit apertures to support the dies used, means to coat the strand including a die of resilient material having an aperture therethrough of approximately the diameter of the strand, the die being so formed as to have a deep annular groove in its side surfaces and the lower portion of the die cut out in part to permit the coating material to reach the grooved portion so as to exert a pressure thereon. By using a die of this shape the coating material passes freely through the openings in the lower part of the die and is able to press on the narrowed portion of the die. Since the pressure exerted on this portion of the die will be about the same as the pressure exerted at the die aperture, the tendency of the coating material to force its way out through the die will be compensated by the compression of the walls of the die by the coating material. Any increase in pressure, and consequently an increase in the tendency for the material to escape, will, in short, result in commensurate compression of the die walls. This has been found to adequately compensate for changes in pressure.

Other objects and advantages will appear from the following detailed description of one embodiment of the invention taken in connection with the accompanying drawing wherein:

Fig. 1 is a view in vertical transverse central section of an apparatus for coating strands and constructed in accordance with the invention.

Fig. 2 is a central section of the left hand die of Fig. 1.

Fig. 3 is a plan view of the die shown in Fig. 2.

In the embodiment of this invention shown on the accompanying drawing a metal casing 10 is shown having apertures 11, 12, 13 and 14 suitably spaced therein. The walls 15 of said apertures are extended at right angles to the casing a suitable distance and threaded to receive threaded metal caps 16, 17, 18 and 19. The upper, the exit, apertures 11 and 12 are conically shaped to receive dies 29 and 30. The lower caps 18 and 19 are so designed that a portion 25 forms an inlet die integrally therewith and extends into the apertures 13 and 14 in the casing. This portion is apertured at 26 to permit free passage of a strand 27. Thus these lower caps and their integral dies act as guides for the strand. The strand initially passes through dies 28 and 30 and then after the coating has been hardened by suitable means the coated strand is passed

through dies 26 and 29. The speed with which the strand may be drawn through the apparatus is preferably in excess of 1,200 feet per minute and at this speed any coating material which might tend to extrude through the lower dies is largely returned at once. Since the strand is nearly dry and, therefore, unlubricated when it reaches the lower caps it is necessary in order to reduce friction to use apertures in the caps substantially greater in diameter than the size 10 of the strand with which they are to be used. Satisfactory results have been obtained with a passage of .125" when using a wire of .046" in diameter.

The casing 10 is filled with coating material under a pressure of from 60 to 80 pounds per square inch. Coating material of a viscosity of 25,000 poises at 75° Fahrenheit works satisfactorily. Means for introducing the material into the chamber and maintaining pressure thereon are conventional and well known to the art, and therefore are not shown. Means, of course, are also provided for feeding the strand and pulling it through the machine. These means are conventional and are not shown. Means such as disclosed in the patent to E. E. Newton et al. 2,260,860 and the patent to F. R. Reevely 2,218,482 may be employed.

Figs. 2 and 3 show the rubber die 30 having a deep groove 31 which extends annularly around the outside of the die. The lower portion 32 of the die 30 is cut away segmentally forming a spider shaped head to permit free access of the coating material to a center portion 33 of the die, the purpose being to permit the coating material to exert pressure on this center portion. Enough of the lower portion of the die is left to provide support for the die. The upper portion 34 is solid and disc shaped to prevent escape of coating material. A passage 35 of about the same size as the strand with which the die is to be used is formed in the die. The exit and entrance of this passage are chamfered to prevent "popping."

The die 29 is also made of rubber and is of frusto conical shape. A passage 36 is provided through the center of the die of about the same size as the strand with which the die is to be used. The exit and entrance of this passage are chamfered to prevent "popping." This die is used to produce a final finish on the strand.

It is the particular purpose of the present invention to make a strand having a coating of thick pasty, almost solid, viscous material, 5 or 6 times as thick as that which can be applied on a strand by the relatively thin coating materials heretofore used. This is highly advantageous because the number of coating passes of the strand, therefore, is cut to $\frac{1}{5}$ or $\frac{1}{6}$ the number of those heretofore required to produce coats of like final thickness. Also the volume of solvent required to be evaporated off and either wasted or expensively recovered is very materially lessened and hence a considerable savings is effected in the cost of the whole operation.

In accordance with the present invention a coating material may be used which contains 58% by weight of solids, largely cellulose acetate and 42% by weight of a liquid solvent, largely acetone. The viscosity of this is about 25,000 poises at 75° Fahrenheit, and at the extrusion 70 temperature of about 105° it is about 18,000 poises. It cannot be poured or transferred in the manner of ordinary liquids except under pressure. Obviously since this contains so much less solvent, the loss of solvent is greatly reduced.

In using the device above described for coating a strand, comprising textile thread served on number 22 wire with the coating preparation above described, the strand 27 is drawn from some suitable supply and is threaded through the passage 26 in the cap 18. The strand is then led across the chamber and thus through the coating material thereon and then out through the rubber die 30. Then the wire passes through suitable means to partially or wholly harden the coating. These means are not shown as they form no part of the present invention. About 50 mgs. of coating material per linear foot are extruded onto the wire in this first pass. The 15 once coated strand is then, as aforesaid, subjected to a hardening operation and then returns to pass upwardly through the cap 19 and then through the wiping die 29. About 20 mgs. of coating material per linear foot are extruded onto the wire in this pass. A range of from 60 to 90 mgs. per linear foot is used, about 70 mgs. of coating material per linear foot being optimum. The cellulose acetate material being under pressure of from 60 to 80 pounds per square inch forms on the strand and is wiped smooth by the dies 29 and 30. A coating of suitable thickness remains on the wire as it emerges from the dies, the thickness being controlled by the size of the bores 35 and 36 and by the hardness of the rubber dies 29 and 30 and by the pressure of the coating material.

As is well known there will, of course, be irregularities in the diameter of the strand, the most frequent cause of such irregularities is splices in the wire or knots in the textile threads served on the wire core. Therefore a die must be used which is resilient. Rubber seems ideally suited to this need; however, dies made of other suitable resilient materials such as neoprene will 40 work equally well. Resilient materials having a hardness rating of between 30 and 70 on a Shore Durometer have been found to work satisfactorily.

The particular design of the die 30 permits 45 considerable distortion in addition to the inherent distortability of the rubber. This has been found to be necessary for the first pass. However, the strand having once been coated and passed through die 30, it has been found to be sufficiently 50 uniform to pass satisfactorily through the die 29, although the die 29 has no special configurations to facilitate dilation or distortion.

The embodiments of the present invention herein described are merely illustrative and may 55 be modified or altered without departing from the scope and spirit of the present invention which is limited only by the appended claims.

What is claimed is:

1. In an apparatus for coating a strand, an 60 extrusion chamber, and a die of resilient material in said chamber having an aperture therethrough for the passage of the strand, the outlet end of the aperture of said die being chamfered to obtain smooth coating of the strand.
2. In a strand coating apparatus, an extrusion 65 chamber to receive plastic coating material under pressure, and an extrusion die of a compressible material mounted in said chamber having an aperture therethrough for the passage of the strand, the center portion of said die being reduced and the base of said die comprising a plurality of radially extending fingers to admit coating material to said reduced portion, and the outlet end of the aperture of said die being chamfered to obtain a smooth coating of the strand.

3. In an apparatus for coating strand material, an extrusion chamber, a guiding die in one side of said chamber, means for supplying coating material to said chamber, and an extrusion die of resilient material in the opposite side of said chamber, said extrusion die having a head, a reduced center portion, and a spider shaped base comprising a plurality of radially extending fingers, the outlet aperture of said die being chamfered to obtain smooth coating of the strand.

4. In an apparatus for coating strand material, an extrusion chamber, a guiding die in said chamber, and an extrusion die of resilient material on the opposite side of said chamber, said extrusion

die having a head, a reduced center portion and a spider shaped base comprising a plurality of radially extending fingers, and the outlet aperture of said die being chamfered to obtain smooth coating of the strand.

5. In an apparatus for coating strand material, an extrusion chamber, a guiding die at one side of said chamber, and an extrusion die of resilient material at the opposite side of said chamber having an annularly recessed portion formed in the outer surface of the central portion of said extrusion die to render the center portion compressible in response to changes in the pressure of the coating material, the outlet aperture of said die being chamfered to obtain smooth coating of the strand.
